United States Patent Office

Des. 229,234
Patented Nov. 13, 1973

229,234

CREDIT CARD IMPRINTER

Tomokazu Kato, Tokyo, Japan, assignor to W. T. Grant
Company, New York, N.Y.

Filed Aug. 4, 1972, Ser. No. 277,877

Term of patent 14 years

Int. Cl. D18—02

U.S. Cl. D64—11 B

FIG. 1

FIG. 2

FIG. 3

FIG. 4

FIG. 5

FIG. 6

FIG. 7

FIG. 8

FIG. 1 is a front elevation of a credit card imprinter showing my new design;

FIG. 2 is a rear elevation thereof;

FIG. 3 is a top plan;

FIG. 4 is a bottom plan;

FIG. 5 is a left side elevation;

FIG. 6 is a right side elevation;

FIG. 7 is a right side perspective; and

FIG. 8 is another right side perspective thereof as it appears with the slidable printer head in a different position.

I claim:

The ornamental design for a credit card imprinter, substantially as shown.
